MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

WORK-HOLDER.

1,164,505.

Specification of Letters Patent. Patented Dec. 14, 1915.

Application filed June 25, 1914. Serial No. 847,233.

To all whom it may concern:

Be it known that I, MONROE GUETT, a citizen of the United States, and resident of Hartford, in the county of Hartford and State of Connecticut, have invented certain new and useful Improvements in Work-Holders.

The object of this invention is to provide a work holder which shall be mechanically operated and actuated to properly present work to the operating member, such as a grinding wheel, buffing or polishing wheel, although the invention in its broader aspect may be applicable for holding and presenting work to operating or work-performing devices of another character.

The embodiment of the invention selected for illustration is concerned with a mechanism adapted for presenting work to a grinding or polishing wheel, and Figure 1 is a front view of the mechanism. Fig. 2 a side view thereof. Fig. 3 a top view partly in section. Fig. 4 a detail plan view of the work support. Fig. 5 a sectional view on the line 5—5 of Fig. 4.

This work holder as illustrated comprises a rectangular frame A made up of side members a, a lower transverse member b and an upper transverse member c. This frame is pivotally supported at its lower end as indicated at d, occupies an inclined position as clearly seen in Fig. 2, and is adjustably supported by the rod e equipped with adjusting and locking devices e¹, e². Mounted on the upper frame member c, is a bearing 2 in which is mounted a shaft 3 carrying at its inner end a worm 4, and has loosely mounted on its outer end a driving pulley 5 which may be connected with any suitable source of power and connected to the shaft 3 by the clutch 6 having an actuating handle 7 and a trip lever 8. The upper ends of the side members a, a of the frame project beyond the upper transverse frame member c and support a shaft 10 upon which is rotarily mounted a gear 11 which meshes with the worm 4. There is also mounted on this shaft a secondary frame 15 which reciprocates longitudinally thereon, being moved by a sleeve 16 on the gear 11 which engages a roller 17 at the end of an arm 18 which is fast to this secondary frame. A spring 19 connected with this secondary frame tends to hold the roller 17 against the end of the sleeve 16 which is fluted, and consequently as

the gear 11 and its sleeve 16 rotate, driven by the worm 4, the secondary frame is caused to reciprocate longitudinally on the shaft 10.

The work-holding arm 20 is mounted in the following manner: A rectangular block 21 is rotarily mounted on the ends of the secondary frame, and the arm 20 has an apertured end 22 which fits and slides upon this block so that the arm as a whole has a movement transversely of the shaft 10 as well as rotarily with respect thereto. At the end of the arm 20 is the work receiver 25 offset laterally therefrom and having a suitably shaped shoe 26 secured to its rear wall, which bears against a stationary presser foot 27, the contacting portion of which is preferably a ball, as indicated at 28. The arm 20 also carries a roller 30 which cooperates with a cam 31 mounted on a shaft 32, which shaft is carried in the bearing 33 mounted on the secondary frame 15, and carries at its opposite end a wide gear 34 which meshes with the gear 11.

X indicates the work-producing wheel, such as a grinding, or buffing wheel mounted on a shaft Y, the driving mechanism of which is not shown but may be of any construction and arrangement desired.

The operation of the mechanism is as follows, assuming of course that the polishing or grinding wheel X is being driven: The work-holding arm 20 is raised from the position shown in Fig. 2, and a piece of work placed on the work receiver 25. The arm 20 is then lowered until the roller 30 rests upon the cam 31. By the handle 7 the clutch 6 is then thrown in, connecting the driving pulley 5 with the shaft 3, carrying the worm 4 which meshes with the gear 11, which in turn drives the gear 34 and the shaft 32 carrying the cam 31. The wheel X rotating in the direction of the arrow tends to draw the arm 20 downwardly, holding the roller 30 against the surface of the cam 31. The work-holding arm is shifted transversely of the shaft 10 by the engagement of the curved rear surface 26 of the work receiver 25 with the presser-foot 27, and the work receiver is quite rapidly shifted transversely of the wheel X by the engagement of the fluted end of the sleeve 16 with the roller 17 on the arm 18 connected to the secondary frame. The cam 31 allows the arm to drop until the entire surface of the work has been subject-

ed to the action of the wheel, and then raises the wheel until the work is disengaged from the wheel, and all the time the work is engaged with the wheel it may be shifting transversely of the face of the wheel if such action is desirable. When the shafts 10 and 32 have made one complete revolution, a trip 35 on the gear 11 engages the trip arm 8 and throws out the clutch 6, bringing all parts to rest except of course the wheel X. The piece of work is removed and another piece placed on the work receiver and the same operation repeated. The frame can be adjusted to proper position so as to bring the work receiver into proper relation with the wheel by operating the adjuster e¹ on the rod e, and then locking it in position by the lock e².

In order to accommodate inequalities in the work and in the surface of the wheel X, it is advisable to make the work receiver in two parts, comprising a back plate 40 with channels 41 in which ribs 42 on the front plate 43 fit, springs 44 locked in recesses in the back plate 40 bearing against the front plate 43 to force it out against the wheel. The work is directly supported by the front plate 43, and these springs 44 are stiff enough to provide a proper pressure of the work against the wheel, but will yield under the inequalities of the face of the wheel so as to produce an even and uniform finish on the work.

The particular machine here illustrated is designed for the polishing and finishing of face plates used in connection with electric switches, but the work receiver can be shaped to receive any shape of an article, and the shoe given such a contour as will always hold the work against the wheel, and the mechanical operation of the various parts insures an evenness and uniformity of finish which it is very difficult, if not impossible, to secure by hand polishing or grinding operations.

It will be readily understood that in adapting this work holder to different uses, minor changes in its construction and in the arrangement of its various parts may be necessary, and it is my intention that the appended claims shall cover any and all modifications which come fairly within the scope of the invention.

I claim as my invention:

1. In a machine of the character described, a main frame, a shaft mounted in said frame and supported in bearings in the side members thereof, a work receiver pivotally mounted upon said shaft and slidably supported for longitudinal movement transversely thereof; and separate means for imparting pivotal and sliding motion to said receiver.

2. In a machine of the character described, a main frame pivotally supported at its

lower end, an adjustable support for the upper end of said frame, a work receiver pivotally mounted at the upper end of said frame, supported for reciprocating motion in said frame in a plurality of directions. 70

3. In a machine of the character described, a main frame pivotally supported at its lower end, an adjustable support for the upper end of said frame, a work receiver pivotally mounted at the upper end of said frame, supported for simultaneous reciprocating motion in said frame in a plurality of directions. 75

4. In a machine of the character described, an adjustably mounted main frame, a work holder pivotally mounted in said frame and supported for reciprocating motion in a plurality of directions relative to said main frame, combined with separate means for producing the specified reciprocating motions, and with additional means for producing in part the pivotal motion. 80

5. In a machine of the character described, a main frame pivotally mounted at its lower end, an adjustable support for the upper end thereof, a shaft mounted in the upper end of said main frame and supported in bearings in the side members thereof, a gear rotatable on said shaft and driving means therefor, a bearing slidably mounted on said shaft, a work-holding arm pivotally mounted on said shaft, means for moving said bearing and arm longitudinally of said shaft, and means for moving said arm relative to said bearing transversely of said shaft. 90

6. In a device of the character described, a main frame, an adjustable support for said frame, a work receiver pivotally mounted on said frame, means for moving said work receiver longitudinally, means for moving said work receiver laterally from side to side of said frame, and means for moving said work receiver pivotally. 100

7. In a device of the character described, a frame, a shaft supported therein, a secondary frame mounted for reciprocatory movement along said shaft, a work receiver pivotally mounted on said secondary frame, means for imparting a reciprocatory motion to said secondary frame and its attached work receiver relative to said main frame, and means for moving said work receiver relative to said main and secondary frames both transversely and rotarily of said shaft. 110

8. In a device of the character described, a frame, an upper frame member having front and rear extensions, a shaft mounted on the rear extension of said upper frame member, a driving pulley and a worm mounted on said shaft, a second shaft supported at the upper ends of the side members of said frame, a gear mounted on said shaft and meshing with said worm, a secondary frame mounted on said shaft, a 120

- cam carried by said gear, a roller carried by said secondary frame and actuated by said cam to move said frame longitudinally of said shaft in one direction, means to move 5 said secondary frame longitudinally of said shaft in the opposite direction, a work holding arm carried by said secondary frame and rotarily and longitudinally movable with respect thereto, a bearing carried by said secondary frame, a shaft mounted in said bearing, a gear on said shaft meshing with the first mentioned gear, and a cam at the opposite end of said shaft coöperating with said work holding arm.
- 10 9. In a device of the character described, a frame, an upper frame member having front and rear extensions, a shaft mounted on the rear extension of said upper frame member, a driving pulley and a worm 20 mounted on said shaft, a second shaft supported at the upper ends of the side members of said frame, a gear mounted on said shaft and meshing with said worm, a secondary frame mounted on said shaft, a sleeve carried by said gear, a roller carried by said secondary frame and actuated by said sleeve to move said frame longitudinally of said shaft in one direction, a spring 25 to move said secondary frame longitudinally of said shaft in the opposite direction, a work-holding arm carried by said secondary frame and rotarily and longitudinally movable with respect thereto, a bearing carried
- 30 by said secondary frame, a shaft mounted in said bearing, a gear on said shaft meshing with the first mentioned gear, a cam at the opposite end of said shaft coöperating with said work-holding arm, and a presser-foot carried by the front extension of said main frame and adapted for coöperation with said work-holding arm to move it longitudinally.
10. In a machine of the character described, the combination with a frame and a work-holding arm swingingly mounted thereon and adapted for longitudinal motion transversely thereof, of a presser foot carried by said frame, and a shoe on said work-holding arm adapted for coöperation with said presser foot as said arm swings to produce the longitudinal motion thereof.
11. In a machine of the character described, a main frame, a secondary frame, means for moving said secondary frame laterally from side to side of said main frame, and a work-holding arm carried by and movable with said secondary frame and adapted for movement relatively to said main frame in a plurality of directions.
12. In a machine of the character described, a work receiver comprising a back plate, and a front plate yieldingly supported on said back plate.

MONROE GUETT.
